United States Patent Office.

ALFRED DART, OF CARBONDALE, PENNSYLVANIA.

Letters Patent No. 72,610, dated December 24, 1867.

IMPROVEMENT IN COAL-STOVES.

The Schedule referred to in these Letters Patent and making part of the same.

TO ALL WHOM IT MAY CONCERN:

Be it known that I, ALFRED DART, of Carbondale, in the county of Luzerne, and State of Pennsylvania, have invented a new and improved Stove for Burning Culm and other Fuel; and I do hereby declare the following to be a full, clear, and exact description of the same, reference being had to the accompanying drawings, forming part of this specification, and in which—

Figure 1 is a vertical elevation of my invention, a portion of the wall being broken away to show the interior construction of the stove..

Figure 2 is a horizontal section of my invention through the line *x x*.

Figure 3 is the same through the line *y y*.

Similar letters of reference indicate corresponding parts in the several figures.

In this invention the stove is so constructed that the fuel will be burned in thin strata, in order that oxygen may pass freely through it and thereby better keep up combustion.

In order that others skilled in the art to which my invention appertains may be enabled to make and use the same, I will proceed to describe it in detail.

In the drawings, A represents the outside wall of my improved culm-burning stove, resting on feet B B, and pierced with openings C C of any form that the fancy may suggest. This outer wall encloses the fire-pot D, and a hot-air chamber, E, near the top of the stove. The fire-pot is connected with the hot-air chamber by means of several pipes G G G, arranged in a circle around a large pipe, F, which extends from the fire-pot through the chamber E to the top of the stove, where it is provided with a cover, L. The bottom of the fire-pot D is formed by the grate H, a common horizontally-vibrating or shaking-grate, in which there is but one new feature, namely, a cone, I, rising from its centre to the top of the fire-pot, directly under the pipe F, and corrugated or provided with several wings i i i, which project out from its sides among the fuel. K is a flue, through which the gases, smoke, &c., escape to the chimney. M is an ash-chamber under the grate.

The object of my invention is to procure as complete a combustion as possible, together with the utmost attainable radiation of heat. The latter is secured by the above-described construction, in which the heat is radiated from the fire-pot D, chamber E, pipes F and G G G, and the whole outer wall and top of the stove forming an extent of radiating surface not to be found in any other now in use. The former is secured chiefly by the low, flat, wide shape of the fire-pot, and by the central cone I, which forces the burning fuel out against the walls of the fire-pot. The fuel is fed through the central pipe F, and as it burns away in the fire-pot it presses down from the pipe and keeps the supply of fuel good for a long period. The pipe F is intended to be from one-third to one-half the diameter of the fire-pot D, and the chamber E. The diameter of the pipes G G will vary according to the number of them used.

Having thus described my invention, what I claim as new, and desire to secure by Letters Patent, is—

The central cone I, when provided with the wings i i, and attached to the grate, substantially as and for the purpose specified.

ALFRED DART.
